AIRCRAFT GAS TURBINE ENGINE OR SIMILAR ARTICLE

Gerald W. Lawson, Lynnfield, Mass., assignor to General
Electric Company, a corporation of New York

Application May 4, 1955, Serial No. 35,802

Term of patent 3½ years

(Cl. D71—1)

Fig. 1 is a perspective view of an aircraft gas turbine engine showing the new design;

Fig. 2 is a top plan view thereof;

Fig. 3 is a rear elevational view thereof; and

Fig. 4 is a front elevational view thereof.

The dominant features of my design reside in the portions shown in full lines.

I claim:

The ornamental design for an aircraft gas turbine engine or similar article, as shown and described.
